UNITED STATES PATENT OFFICE

168,455

WALL SHELF

Ellis M. Johnson, Chicago, Ill.

Application April 14, 1952, Serial No. 19,318

Term of patent 7 years

(Cl. D33—3)

To all whom it may concern:

Be it known that I, Ellis M. Johnson, a citizen of the United States, residing at Chicago, State of Illinois, have invented a new, original, and ornamental Design for a Wall Shelf, of which the following is a specification, reference being had to the accompanying drawing, forming a part hereof.

Figure 1 is a front elevational view of a wall shelf showing my new design.

Figure 2 is a top plan view thereof.

Figure 3 is an end elevational view thereof; and

Figure 4 is a front perspective view of the same.

I claim:

The ornamental design for a wall shelf, as shown.

ELLIS M. JOHNSON.
